UNITED STATES PATENT OFFICE.

CHARLES F. KETTERING AND WILLIAM A. CHRYST, OF DAYTON, OHIO, ASSIGNORS TO
THE DAYTON ENGINEERING LABORATORIES COMPANY, A CORPORATION OF OHIO.

ENGINE-STARTING SYSTEM.

1,243,422.

Specification of Letters Patent.

Patented Oct. 16, 1917.

Original application filed July 14, 1913, Serial No. 778,934. Divided and this application filed August 13, 1915. Serial No. 45,412.

To all whom it may concern:

Be it known that we, CHARLES F. KETTERING and WILLIAM A. CHRYST, citizens of the United States of America, residing at 5 Dayton, county of Montgomery, and State of Ohio, have invented certain new and useful Improvements in Engine-Starting Systems, of which the following is a full, clear, and exact description.

10 This invention relates to a system of devices adapted for supplying power to start an engine, and the engine when thus started, is arranged to store up power for similar future starting operations, and this same 15 power source may then be used to supply current for the ignition system of the engine, and for any other purposes which may be desired.

That is, in the particular form hereinafter 20 described as embodying our invention, we have provided an automatic starting system, which is particularly adapted for use in connection with motor vehicles, wherein, an engine forms the power plant, or a part of 25 the power plant, so as to eliminate the manual starting of the engine, and to facilitate the automatic starting thereof.

While this invention is primarily shown and described as being preferably adapted 30 to be employed in connection with automobiles or motor vehicles, it may be readily combined with any type of power driven apparatus or machines, wherein it is necessary to apply an initial starting power there- 35 to, in order to bring the normal actuating or driving power of the apparatus or machine into action.

It is among the general objects of this invention to produce novel combinations of 40 mechanisms, and to simplify the structure and assembling thereof, and make their operation more efficient for the various purposes and requirements which they are adapted to fulfil.

45 In accomplishing the above objects, the present invention provides novel means for controlling the different units of the system in a simple and convenient manner, requiring a minimum amount of attention and 50 skill on the part of the operator.

As has been heretofore stated, the present

invention has for one of its objects, to simplify the construction and assembly of the various elements and combination of elements, which make up the present invention, 55 and to further simplify and facilitate the application of the system, as a whole, to the apparatus or vehicles, with which it may be combined.

The above is accomplished in part by employing a portion of the frame or chassis of the apparatus or vehicle, to which this system is applied, as one side of the various electric circuits included in the system, thus 60 eliminating certain of the wire circuit connections usually employed in systems of this type.

This, of course, results in the reduction of the necessary wiring, and permits the accomplishment of functions necessary to a 70 system of the present type, in a greatly simplified manner.

Up to the time of the present invention, practically all systems embodying starting devices of the electrical type, such as for 75 instance, as are included in the co-pending application filed September 19, 1912, Serial No. 721,237; and U. S. Patents 1,171,055, issued February 8, 1916, and 1,150,523, issued August 17, 1915, comprised in general a 80 source of current, for instance, an accumulator or storage battery, and a motor and a generator, either combined in a single unit or embodied in separate and independent units. The above mentioned units generally 85 have electrical connections between the electric machine, or machines, and the storage battery, and mechanical connections between the said machine or machines, and the engine, together with controlling mechanism 90 which comprises a switch unit for selecting the electrical connections and any suitable means for controlling the mechanical connections.

Now, it is one of the primary objects of 95 the present invention to simplify this controlling mechanism, and to eliminate certain of the units of the system, by so constructing, arranging and combining other elements thereof, which are already employed to perform given functions, that they 100 will be capable of operation, to perform not

only their own original functions, but also the functions of the eliminated elements or mechanisms.

An instance of one manner in which the above named objects may be accomplished in the present invention is by the elimination of the independent switch unit which is adapted to control the connections between the accumulator and the electric machine. This elimination of the switch is permissible by the novel construction and arrangement of the commutator brushes employed in the electric machine and the means for operating said commutator brushes to accomplish the various functions which were formerly accomplished by the independent switch unit.

The novel arrangement and combination of the brush unit does not interfere with the original and regular functions of the brushes, but simply permits them to perform not only their own function, but the additional functions of the switch.

A further object of the present invention is to provide a dynamo-electric-machine, having a plurality of sets of independent field and armature windings, the respective sets of armature windings having independent commutators and sets of commutator brushes, these commutator brushes being so combined with controlling mechanism that the selection of the set of windings to be operatively connected, may be controlled by the position of the brushes, which is determined by the operation of a controlling mechanism.

Thus, it is possible to have a dynamo-electric-machine embodying separate motor and generator field and armature windings which are connected in turn with independent commutators, and commutator brushes, in combination with controlling mechanism, which will normally maintain one set of commutator brushes in such position as to normally break the circuit connections between this set of field and armature windings, and to establish a circuit through the other set of armature and field windings, this controlling mechanism being preferably so arranged as to operate the displaced brush or brushes, to bring the same into electrical connection with their own commutator, and to concurrently break the other electrical connection which is formed by the brush when in its normal position.

A further object of the present invention is to provide an electric machine having commutator brushes and brush-holders automatically movable to compensate for inaccurate associated structures, such as the uneven surfaces of the commutator, and capable of another operation to make or break certain electrical connection between the battery and the electric machine.

In the U. S. Patent to Charles F. Ketter-

ing, No. 1,150,523, issued August 17, 1915, it is set forth that one of the objects of the invention is to secure a preliminary movement of the electric machine, in order to facilitate the shifting of the connections between the said machine and the engine, so as to connect the machine to the engine for starting purposes.

As an illustration of one manner in which this object may be accomplished, the above application and patents set forth the use of a supplemental circuit between the electric machine and the accumulator, of such resistance that only a small amount of current, at a relatively low voltage, would pass from the accumulator to the dynamo-electric-machine. This reduced flow of current from the battery to the electric machine was intended to effect an initial movement of the machine as a motor, and in this way to facilitate the shifting of the connections between the engine and the motor.

Another object of the present invention is to secure this preliminary movement of the electric machine by the operation of a movable commutator brush, previous to the normal starting operation of the machine. This preliminary movement may be secured without necessarily employing an independent circuit and also without requiring a separate and independent manual operation to secure the desired result.

One manner of accomplishing the above object is to include a circuit interrupter or cut-out relay in the circuit connections between the generator and the accumulator, its primary functions being to automatically prevent the current flowing back from the battery to the electric machine, at such times as the voltage across said machine is less than the voltage across the terminals of the battery, and to provide mechanism, whereby said cut-out relay or interrupter may be closed automatically and previously to the operation of the controlling mechanism, for effecting the actual starting of the engine.

However, it will appear that various other means may be employed to secure the above result, as for instance, by the insertion of a resistance element in the motor circuit, and having mechanism whereby this resistance element will be maintained in series with said circuit, for a short period of time, as a preliminary to the use of the electric machine for starting purposes, and then having mechanism which will operate to short-circuit said resistance, as soon as the shiftable connections have been actuated, thus permitting the electric machine to be operated as a motor in such a manner as to efficiently perform its required functions of cranking the engine.

Further objects and advantages of the present invention will be apparent from the following description, reference being had

to the accompanying drawings, wherein preferred forms of the present invention are clearly illustrated.

In the accompanying drawings:

5 Figure 1 is a top plan view of the chassis of an automobile, showing one manner of applying the present invention to vehicles of this type.

10 Fig. 2 is a view similar to Fig. 1, showing, on an enlarged scale, the engine and electrical machine, with the mechanical connections for coupling the engine and electric machine together. This view also shows a modified form of the main controlling mechanism.

15 Fig. 3 is a partly diagrammatic and partly structural view of one form of the present invention, the structure of the vehicle and its chassis being eliminated, except for one side frame, for the sake of clearness.

20 Fig. 4 is a view in side elevation of one type of an electric machine which may be advantageously embodied in the present invention, this view also disclosing partly in dotted lines, a preferred form of the controlling mechanism.

Fig. 5 is a view in end elevation of the electric machine shown in Fig. 4.

25 Fig. 6 is a detail view of the movable commutator brush and holder, together with their associated parts.

Fig. 7 is a detail perspective view of one of the commutator brushes.

30 Fig. 8 is a modified form of the structure shown in Fig. 4.

Fig. 8^a is a fragmentary end elevation of Fig. 8.

35 Figs. 9, 10 and 11 are views, partly diagrammatic and partly structural of modified forms of the invention disclosed in Figs. 1 to 5 inclusive.

40 Fig. 12 is a view in side elevation of the electric machine disclosed in Fig. 11, certain parts thereof being shown in section for the sake of clearness.

Fig. 13 is a detail plan view of certain of the mechanical structure shown in Fig. 12.

45 Fig. 14 illustrates a modified form of the brush-holder shown in Figs. 11 and 12.

50 The present application is a division of our co-pending application, filed July 14, 1913, Serial No. 778,934.

55 Referring to the drawings, and more especially to Figs. 1 to 7 inclusive, it will be noted that there is disclosed an auxiliary system for motor vehicles, which is adapted to supply power to start the engine of the vehicle, and at the same time to provide means whereby, when the engine is brought into operation, power will be stored up to supply current for the lighting and ignition systems as well as for any other purposes which may be desired, as for instance, for signaling.

60 65 Inasmuch as the present invention is pref-

erably adapted to be applied to motor vehicles or other types of vehicles, it will be obvious that the system should be as simple as possible, and at the same time, that the elements thereof should be so constructed and arranged as to give the greatest possible efficiency with the least liability of excessive wear and tear or breakage.

In Figs. 1 and 2, the numeral 20 designates the side frames of the chassis, while 70 the numeral 21 indicates the engine, provided with the fly-wheel 22, having gear teeth 23 cut on its periphery. The type of chassis and engine construction shown in the present instance is similar to that manufactured and placed on the market by the Cadillac Motor Car Company, and comprises the usual four cylinder four cycle engine, adapted to drive through a power transmission contained in the case 26, the various elements of this transmission being controlled by means of a lever 28, which is movable to secure the several different speeds forward, and the reverse speed, in the ordinary manner.

80 Fig. 3 is a partly diagrammatic and partly structural view of one form of the present invention, the structure of the vehicle and its chassis being eliminated, except for one side frame, for the sake of clearness.

85 Fig. 4 is a view in side elevation of one type of an electric machine which may be advantageously embodied in the present invention, this view also disclosing partly in dotted lines, a preferred form of the controlling mechanism.

90 The dynamo-electric-machine, which may be termed the prime mover of the present invention, is designated by the numeral 30, and is adapted to be driven as a generator, during the normal operation of the engine, by means of the timing gears 31 and shaft 32, as is clearly shown in Fig. 2.

95 The location and arrangement of the dynamo-electric-machine is substantially the same as shown in the co-pending application of Charles F. Kettering, filed September 19, 1912, Serial No. 721,237, and U. S. Patent 1,150,523, issued August 17, 1915, but it will be understood that this unit may be located on any part of the machine, the only restriction being that it be in such a position that it will efficiently perform the desired and intended functions.

100 The battery 34 is preferably contained in a box or casing 35, located on the running board of the machine, or in any other convenient place. In the present type of system, there are no mechanical connections between the battery and any of the other elements of the machine, other than the wire connections, and it will therefore be apparent that the location of the battery box and battery may be made with regard to convenience only.

105 In practically all types of motor vehicles now in service, the side frames of the chassis are made of steel or alloy metals, which are of low electrical resistance, and which makes a practicable ground mass. In view of this fact, the present invention contemplates 110 what may be termed a single wire system, that is, there will be a single wire running from the battery to the electric machine, there making whatever connections may be necessary with different branch wires to con- 115

120

125

130

duct current from or to the generator and motor, and to supply current for lighting, ignition and other systems. This wire will constitute one side of the main circuit, while 6 the other side of the main and the various branch wire circuits are made through the frame of the machine, which will be termed hereinafter, the mass or ground side of the circuits.

- 10 In Fig. 3, there is illustrated an electric machine of what may be termed the dynamo-electric-machine type, which may have its field and armature windings so arranged and constructed that it may be operated as 15 a generator for the purpose of charging the accumulator or providing current for ignition or lighting purposes, and again, as a motor for starting purposes.

Referring particularly to Figs. 1 and 3, 20 one terminal 41 of the battery 34, is connected to the frame 20 of the chassis, while the other terminal of the battery leads through the wire 45, directly to the terminal 43, which is secured to but insulated from 25 the dynamo-electric-machine. This wire 45 constitutes what may be termed the common connection between both the motor and generator windings of the electric machine and the storage battery.

30 The lighting system for the automobile may have a wire 46, connected to the wire 45, the various lamps being connected thereto in series parallel, the opposite side of each lamp circuit being connected in turn 35 to the ground or mass connection 20.

A similar arrangement may be applied to the ignition system, which consists of a wire 47, connected to the wire 45, at the terminal post 43, and leading to the usual induction 40 coil 49, and timer 50, the opposite side of said ignition system being connected to the frame of the chassis, by any suitable connection 53. This construction not only reduces the cost of applying the system to the vehicle, but it also greatly simplifies and 45 renders more efficient the entire system.

In all electrical systems where there are various wire connections, it is extremely desirable to eliminate as many soldered joints, 50 or connections, between the different wires, as is possible, and in the present case, by having the terminal 43 so arranged as to receive not only the wire 45, but also the wire 47, it will be apparent that certain of 55 what would otherwise be soldered connections, have been eliminated, and if desired, other wires such as 46 can be connected at this terminal 43.

In the electric machine disclosed in Figs. 60 3, 4 and 5, the armature and fields are so wound as to constitute what is known in the trade as a series wound motor, and a shunt wound generator, for the reason stated hereinafter.

65 Referring to the various diagrammatic

figures, it will be noted that the wire 45, which is connected to one terminal of the battery 34, leads to a terminal 43, connected with the frame of the dynamo-electric-machine. This terminal is, of course, insulated from the frame in any suitable manner, as by washers 43^a and the sleeve 43^b. The opposite end of the terminal 43 is connected with one end 94 of the heavy or series motor winding 95, and also has a connection with the comparatively high resistance wire 52, which leads to the contact plate 53, of the cut-out relay 54, which is included in the generator circuit.

70 It will be appreciated that when the machine is used as a motor for starting purposes, a high torque effect is required, in order to efficiently crank or turn over the engine, and in the present instance, this high torque effect is secured by employing a series 75 motor, having windings capable of conducting a comparatively high amperage at a relatively low voltage.

75 On the other hand, it is equally desirable that the generator which charges the storage 80 battery, should supply current of such an amperage and voltage as will be proper for the battery to receive, and inasmuch as the proper amperage for charging the battery is much lower than the amperage which the 85 battery discharges to the motor for starting purposes, the generator field and armature windings and certain of their circuit connections are of a relatively lower electrical 90 conductive capacity than the motor windings and their connections.

95 In order that the generator may be operated at a comparatively low speed, and at the same time commence to charge the storage 100 battery as quickly as possible, after it has started to operate, a shunt wound type 105 of machine is employed.

100 Referring to Fig. 3, the series winding 95 of the motor is connected at one end to the 110 terminal 43, and at the other end with the commutator brush 61, the opposite commutator brush 62 being carried by the pivoted brush-holder 63, which is of conductive material, and is grounded by being secured to the generator frame, the ground connection 115 shown in the various figures, being simply illustrated for the sake of clearness.

115 In Fig. 3, the brush-holder 63 is shown diagrammatically, but its more exact shape for practical mechanical construction is 120 shown in Figs. 4 and 5, with details as per Figs. 6 and 7.

120 Referring to said figures, it will be seen that the movable brush-holder 63 is of right angle construction, one arm 63^a carrying the 125 brush 62, while the opposite arm 63^b is provided at its extremity with a roller 64, against which operates the cam surface 65^a, formed on the angle lever 65. This angle lever is pivotally mounted on the interior 130

of the generator frame, as at 66, and is connected with the rod 67, which extends rearwardly and may be secured in any suitable manner to the bracket of a magnetic latch mechanism 68.

The construction and arrangement of this latch mechanism is substantially the same as that employed in the U. S. Patent to Charles F. Kettering, No. 1,150,523, issued 10 August 17, 1915, and therefore reference may be made to this application for a more detailed description and illustration of the elements comprising this structure.

In general, the magnetic latch mechanism 15 comprises a bracket and armature pivotally connected with the rod 67 and carries a magnet coil. This bracket, coil and armature are normally loosely mounted on the clutch shaft 69. This coil and armature 20 construction is so arranged that when current is passed through the coil, the armature will be brought into position to engage with a projection or arm which is rigidly fastened to the clutch shaft, thus effectually 25 coupling the magnetic latch unit and consequently the shaft 67 with the clutch shaft 69 and pedal 90, it of course being understood that this rigid arm will be normally in such a position as to oscillate with the 30 movement of the clutch shaft 69, free from engagement with the armature of the magnet.

Now, as soon as the magnetic latch has been operated and the clutch pedal is depressed, the rod 67, which is connected with the magnetic latch, will be drawn rearwardly and the shiftable gearing 91 will be drawn into enmeshment with the armature pinion 92 and the toothed portion 23 of the fly wheel. This rearward movement of the rod 67 will also actuate the cam lever 65, so as to permit the spring 105 to initially move the commutator brush out of engagement with the contact plate 80, and thus 35 break the generator or charging circuit, and next to engage with the motor commutator and thus complete the motor circuit.

The sequence of the above mentioned operations will be as follows:

50 The gearing 91 will be shifted into engagement with the armature 92, and the toothed portion of the fly-wheel, previous to the time that the brush-holder 63 is moved away from contact plate 80 and the contacting of the movable motor brush with the motor commutator will not take place until 55 after the gearing 91 is properly meshed with the armature pinion and the fly-wheel.

In certain instances, it may not be desirable to employ the clutch pedal as the main operating element, and in this case, a construction similar to that shown in Fig. 2, may be employed, wherein the shaft 69^a will 60 carry an operating pedal 69^b, which will, in this type of construction, constitute the

main operating member for the starting system.

This shaft 69^a has fastened upon it a bell crank lever 69^c which is directly connected with the shifting rod 67. Thus upon pressing the operating pedal 69^b the rod 67 is directly and positively operated to shift the starting gears and to change the electrical connections as above stated without the intervention of the magnetic latch arrangement just referred to. But, if desired, this magnetic latch arrangement may be utilized in connection with the pedal 69^b, so that the pedal only operates the rod 67 when the magnetic latch is operated in the manner 75 described in the aforesaid application.

It will, of course, be understood that when this separate operating pedal 69^b is utilized for the purpose of shifting the rod 67, the clutch pedal 90 is merely the ordinary clutch pedal for shifting the clutch connection between the engine and the driving gear of the vehicle or between the engine and the transmission, in the ordinary manner. The first of these forms is shown 80 in Fig. 1, with the clutch pedal for shifting the starting gears; and the other form is shown in Fig. 2, where the separate operating pedal 69^b is used for shifting the starting gears, and the clutch pedal 90 performs 85 its ordinary function as a clutch pedal.

In order to facilitate the assembling of the dynamo-electric-machine and its associated parts, the movable brush element is mounted upon a rod or bar, see Figs. 5 100 and 6, which extends transversely across the front of the machine. This rod is made with an extension 101^a, so that the elements which are carried on the rod may be assembled thereon, previous to the placing of the 105 rod in the frame of the machine.

The brush-holder itself comprises the tubular body portion 102, through which the above mentioned rod 101 passes. It will be apparent that the locating of the brush 110 62 in its correct position, relative to the commutator, forms an important feature, inasmuch as if the brush is not located so that the arc of the contacting face corresponds to the arc of the commutator, only 115 a portion of the brush will be in contact with the commutator.

This leads to various objections, which tend to reduce the efficiency of the machine. The manner of locating this brush element, 120 relative to the commutator, comprises a collar 103, which may be secured on the rod 101, in any suitable position, by simply tightening the set screw 104. This collar, after it is adjusted to properly position the 125 brush, sets as an abutment against which the end face of the brush-holder is pressed, by means of the spring 105, which is mounted between the end of the brush-holder and the second collar 103^a.

This spring not only performs the function of maintaining the brush-holder in its correct lateral position, but one end of this spiral spring is connected with the brush-holder, and the other end to the collar 103^a, as shown in Fig. 6, so that normally, the spring tends to hold the brush in contact with its commutator, and at the same time, provides a resilient connection so that any 10 wear of either the brush or commutator bars will be compensated for by the action of this spring, in drawing the brush into contact with the commutator.

The cam lever 65 is shown in Fig. 4, in 15 its normal position of charging or of rest; that is, the movable brush is in such position that it will normally be out of engagement with its commutator. Upon movement of the main operating pedal 90, the 20 rod 67 moves to the right in Fig. 4, so that the spring 105 will pull the commutator brush downward into engagement with the commutator.

When the brush-holder is held in its normal upward position, a portion of the holder which is adjacent to the brush, will lie in engagement with the contact plate or element 80, and, as will appear hereinafter, the brush-holder itself will form a part of 30 the generator circuit. This contact element 80 is mounted in any suitable and insulated manner upon the casing and is connected by any suitable lead wire, such as 80^a (Fig. 3) to the brush 79.

Corresponding to the field windings of 35 the machine, the armature is of the double wound type, having heavy windings for motor work, and fine windings which are used when the machine is operating as a 40 generator. These windings are connected to separate and independent commutators, it of course being understood that the motor 45 commutator is larger than the generator commutator, and capable of passing or conducting a greater amount of current.

It is thought that a description of the 50 operation of the system, in connection with the wiring diagram, will clearly bring out not only the structure of the various elements, but also the functions of each element separately, and in combination with certain of the coöperating elements.

For instance, in Fig. 3, it will be supposed 55 that the system is in position, wherein the engine of the vehicle is at rest. Now, in order to start the engine, it is, of course, necessary to mechanically connect the motor and the fly-wheel or some other equivalent part of the engine together, and it will 60 also be understood that the series windings of the motor must be brought into electrical connections with the battery.

In systems of the type wherein the 65 mechanical connections between the motor and the engine comprise a shiftable gearing,

it is advisable that some means be provided so that a supplemental or initial movement may be imparted either to the shiftable gearing itself, or to the armature and its pinion, so that if the end faces of the gear 70 teeth of the shiftable gearing happen to rest in alinement with the end faces of the teeth of the armature pinion, or fly-wheel, some means will be provided to move the coöperating gear wheels in such a manner that they 75 will assume the proper position, for coupling purposes.

It will also be understood that because of the fact that the shiftable or coupling gearing will be thrown into engagement with 80 the armature pinion, during this initial movement thereof, that the armature and its pinion should be operated at a comparatively slow speed, and with low torque effect.

One manner of securing this result is to so arrange the electrical connections between the battery and the generator windings of the machine that current can flow from the battery through said windings, 90 and thus operate the machine as a motor, through the generator windings.

However, the generator circuit connections embody an element known as a cut-out relay, which normally constitutes an automatic switch, controlled by the voltage of the battery and the generator, that is, this switch or cut-out relay is so constructed and positioned that when the voltage across the battery terminals is greater than the voltage 100 across the generator brushes, the switch will automatically operate to break the generator circuit, thus preventing the battery from discharging back through the generator windings.

It is therefore necessary, to provide some means for closing this automatic switch or cutting out the effect of the same, at such times as the machine is to be operated as a 110 motor, by use of the generator windings as a preliminary to the actual starting operation.

In Fig. 3, this latter effect may be secured by depressing the push button 70, to close the contact plates 71 and 72, thus permitting a 115 flow of current from the battery 34, through wire 45, to point 48, wire 75, through plates 71 and 72, wire 73, wire 74, through the shunt field windings 76, to ground, and also through wire 74, across the generator 120 brushes 78 and 79, contact plate 80, through the brush-holder 63 of the motor brush, to ground.

The closing of the circuits in the manner described above, will cause the machine to 125 operate as a motor and initially at a slow speed, and with a light torque effect.

As soon as the push button 70 has thus been depressed, the main operating member or clutch pedal 90, shown in Fig. 1, is then 130

depressed so that the shaft 69, Fig. 1, is 5 rocked, and the rod 67 is moved in the direction of the arrow 85, Fig. 3. This will cause an enmeshment of the coupling gearing 91, with the armature gear wheel 92, and the toothed portion of the fly-wheel. At the 10 same time, as shown in Fig. 4, the movement of the rod 67 in the direction shown by the arrow, will allow the spring 105 to rock the brush-holder 63 downward, whereby the contact between the brush-holder 63 and the plate 80 will be broken. This breaks the generator circuit and cuts out the initial 15 movement of the armature, but not until after the coupling gearing has been brought into coupled position to connect the engine and motor together.

Continued movement of the rod 67 in the same direction will allow the spring 105 to 20 move the brush 62 still farther downward into engagement or contact with the motor commutator 93. The following circuit connections will therefore be established. From the battery 34, through wire 45, wire 25 94, series winding 95, across the motor brushes 51 and 62, to the ground connection established by the brush-holder 63. The operation of the machine as a motor, when the coupling gearing has been thrown into coupled position, will instantly tend to crank or turn over the engine, thus having the same effect on the engine to bring the same into self operation, as the well known method of manual cranking.

35 As soon as the engine begins to operate under its own power, the operator releases the pressure from the clutch pedal 90, and by any suitable arrangements of springs or similar devices, the rod 67, together with 40 the coupling gearing 91 and the pivoted brush-holder 63, will be returned to the position shown in Figs. 3 and 4. Such an arrangement of spring device is shown in Fig. 1, wherein the mechanism just back of the 45 flywheel 22 is broken away to reveal the ordinary clutch spring 31^a, as likewise explained in the application, Serial Number 721,237, above referred to.

This spring 31^a is the strong spring customarily used to force the engine clutch members into engaging position, and it is this spring which opposes the downward pressure on the clutch pedal 90, and likewise restores the clutch pedal 90 to normal position.

55 Of course, if a separate operating member 69^b is used, as explained with reference to Fig. 2, any suitable spring device can be similarly used to restore the pedal 69^b to normal position as just explained.

Such a spring is not shown in the drawings, but it is of course obvious that it may be attached at any convenient place to operate as described.

65 However, if the operator maintains the

main operating member in depressed position after the engine becomes self operating, a clutch mechanism similar to that shown in the U. S. patent to Charles F. Kettering No. 1,150,523, issued August 17, 1915, which 70 is interposed between the gear wheel 91^a and 91^b, will permit the gear wheel 91^b to run free with the fly-wheel, independent of the wheel 91^a and the armature.

By referring to Fig. 2, it will be noted 75 that the timing gears 31 of the engine are connected to the shaft 32, which in turn has a roller or friction clutch connection with the armature shaft. This clutch connection may be of any suitable construction, such as is shown in my co-pending application filed September 19, 1912, Serial No. 721,237, and U. S. Patent No. 1,150,523, issued August 17, 1915, and therefore, no detail showing or description thereof will be made. 80 By means of this clutch arrangement, as soon as the engine is started and its speed increased, the clutch picks up the armature shaft so that the engine then drives the generator through the timing gears 31, these 85 clutch connections and the ratios of gearing connections between the engine and the dynamo-electric-machine being as set forth in said applications, to which reference may be had for more detailed description. 95

As soon as the shiftable gearing has been moved out of engagement with the fly-wheel and armature pinion, the machine will be driven as a generator, by the operation of the timing gears, and as soon as the speed 100 thereof is sufficiently increased, an out-put of required voltage will be generated and thus effect the charging of the storage battery.

Referring to Fig. 3, the circuit connections 105 for the machine, when operating as a generator, will be as follows:

From the generator brush 78, through wire 74, through the shunt field winding 76, to ground and through the branch wire 74^a, 110 through the fine winding 96 of the cut-out relay or interrupter, to the ground connection thereof with the generator frame. The other generator brush 79 is connected by wire 80^a to contact plate 80 and this to the 115 brush-holder 63 which is grounded as at 113.

Now, as soon as the current has built up sufficiently to energize the core of the cut-out relay, so as to attract the armature 97 to 120 a position to close the contacts 98, the current will flow through the heavy winding 99, armature 97, contact points 98, contact plate 53, wire 52, to the common connection or wire 45, to the battery and across the 125 battery to ground connection 41.

In Figs. 8 and 8^a, there is shown a slightly modified form of the electric machine and certain of the co-operating elements from that shown in Figs. 4 and 5. 130

In Fig. 8, the operating mechanism for permitting the movable brush-holder 63 to contact with its commutator and the gear shifting mechanism, is shown in such a position that the brush-holder is in its downward position, thus breaking contact with the plate 80 and the coupling gearing 91 is enmeshed with the armature pinion 92 and the toothed portion 23 of the fly-wheel.

For the proper operation of these parts, the first thing which should occur is to have the shifting of the rod 67 bring the gear 91 in mesh with the pinion 92 of the armature. In Fig. 3 it has already been described how the pushing in of the push button 70 causes the slow turning of the motor and of the armature pinion 92. This slow turning, of course, assists in the enmeshment of the gear 91 with the pinion 92, by preventing the conflict of the teeth when the gear 91 is shifted into mesh with the teeth of the pinion 92. Then, immediately thereafter, the gear wheel 91, in its lateral movement (to the right in Fig. 8) goes into mesh with the toothed portion 23 of the fly-wheel.

Similarly, if the parts are stopped so that the teeth of the gear wheel 91 rest in position to conflict with the teeth of the fly-wheel, this slow turning movement will move the teeth of the gear wheel 91 out of alignment, so that they can be brought into proper alignment to mesh with the toothed portion 23 of the fly-wheel.

Thus, this shifting of the rod 67 has now connected up the motor to the fly-wheel of the engine, ready for starting. But, during this time, it is necessary that the contact 80 should be closed by the brush-holder 63 pressing up against it, so as to complete the generator circuit to permit the machine to operate as a motor at this slow speed described. However, this maintaining the contact closed is necessary only for such period of time as will make sure that the gear wheel 91 has properly started into mesh with the armature pinion 92 and the fly-wheel gearing. Of course, the contact 80 might be maintained closed until the gear wheel 91 had just started into engagement with the teeth 23 of the fly-wheel, but this may not be essential because it is only desired to give just enough starting movement to the motor pinion 92 and gear wheel 91 to make such that the starting gears can be shifted without blocking of the teeth.

This momentary holding closed of the contact point 80 therefore takes place while the rod 67 is shifted slightly to the right in Fig. 8, and this does not allow the brush-holder 63 to drop away from the contact 80, on account of the rounded face on the outer end of the arm 65. The initial position of this arm is shown in Fig. 4, wherein the brush is held against the contact 80. Then, as the rod 67 shifts to the right, there

is a slight dwell of the cam arm against the roller 64, so as to hold the brush in contact with the plate 80. Then, a further movement of rod 67 causes the flattened portion 65^a of the arm 65 to be brought opposite the roller 64. This then allows the brush-holder to drop, assisted by the spring 105.

This shifted position is shown in Fig. 8, where the brush-holder is moved down into contact with its armature. When the brush 75 is thus in contact with its commutator, the motor circuit is now closed ready for starting, the generator circuit having been broken by breaking the contact at the point 80.

The parts are now in position ready for starting the engine.

As soon as the engine does start, it will pick up speed and the clutch pedal is then released so as to shift the rod 67 back again 85 to its normal position shown in Fig. 4, whereupon the starting gears are brought out of mesh and the brush-holder brought back to close the contact at the point 80, thus breaking the motor starting circuit and closing the generator circuit, so that the engine 90 will now operate the electric machine as a generator, to charge the storage batteries.

Referring to Fig. 10 of the drawings, the electrical circuits and arrangements are similar to those heretofore described in connection with Fig. 3, with the exception that the push button circuit for securing the preliminary operation of the machine as a motor, at a slow initial speed, is eliminated 100 and a new circuit arranged which bridges the contact points of the cut-out relay. In this figure, it will be seen that the wires 108 and 109 are connected directly with the contact plates 53 and 97 of the cut-out relay, 105 at one end, and with the contact plates 110 and 111 at their opposite end, respectively. The free ends of the plates 110 and 111 carry contact points and the outer plate 110 is of spring construction, normally tending 110 to make contact with the inner plate 111. But plate 110 has a downward extension engaged by an arm 112, carried by the shifting rod 67. This arm 112 holds the contact plates 110 and 111 apart. But when the 115 rod 67 is shifted to the left in Fig. 10, for starting the engine, the contacts 110 and 111 are connected.

When this operation occurs, the flow of current will be as follows: from the battery 120 34, through wire 45, wire 52, contact plate 53 of the cut-out relay, wire 108, contact plates 110 and 111, wire 109, and thence to the heavy winding 99 of the cut-out relay 54, down through the shunt field 76 of the 125 generator to ground; also through the wire 74, across the brushes 78 and 79, contact plate 80, and thence through the motor brush-holder 63, to the ground connection 113.

From the above description, it will appear that only a single movement is necessary to complete the starting operation of the dynamo-electric-machine. That is, the following functions will be accomplished by the single complete movement of the main operating member 69^b shown in Fig. 2.

On the first movement of the rod 67, the projection or finger 112, carried by the rod 10 will retreat from the contact plate 110, and permit the same to spring into engagement with the plate 111. This movement of the rod 67 will not effect the position of the brush-holder because of the delayed movement of the brush-holder, caused by the dwell on its operating cam, as previously explained with reference to Figs. 4 and 8.

Upon a further movement of this rod 67, the gear connection between the armature 20 pinion and the fly-wheel will first be established as already explained. And then, the still further movement of the rod 67 will allow the motor brush-holder 63 to move out of engagement with the plate 80 and into 25 engagement with the motor commutator, thus breaking the generator circuit and establishing the motor circuit in the manner described heretofore in connection with Fig. 3.

It will of course be understood that when the ordinary clutch pedal 90 is used, as shown in Fig. 1, then the slow initial movement, above referred to, is accomplished by depression of the push button 70, so that 35 by this means, the clutch pedal can be used for its ordinary purposes, without always operating the starting mechanism.

Whereas, if a separate operating member, such as 69^b, shown in Fig. 2, is utilized, then 40 this separate operating member has no other function than that of operating the starting devices, and this member 69^b could then be utilized in its preliminary movement to effect the slow initial movement referred to.

In Fig. 9, there is illustrated a still further modified means for securing the preliminary operation of the electric machine as a motor, prior to its actual starting operation. In this modified form, a mechanical means, such as the rod 120, is slidably mounted on the rod 67, and so arranged that the lug 120^a normally forces said arm 120 into such position that its free end lies adjacent to but spaced apart from the armature 97 of the cut-out relay. This rod is held in its normal position against the tension of the spring 120^b. The function of this spring is to draw the arm 120 to the left, in Fig. 10, as soon as the rod 67, carrying the lug 120^a, is moved to the left.

A further modification illustrated in this view is the arrangement of the movable brush-holder, relative to the pair of contact plates which form a part of the generator circuit. In this instance, the movable brush-

holder 124 is insulated from the frame of the machine, and therefore does not form a part of the generator circuit at any time, but is of course included in the motor circuit. However, when this switch is in its 70 normal position, it tends to break the motor circuit and to make the generator circuit, by closing the contact plates 128 and 129.

The flow of current through the motor connections, for starting, in the form shown 75 in Fig. 9, will be as follows: from the battery 34, through the wire 45, through the wire 94^a, series winding 95^a, across the brush 62, through the armature to the brush 61, and thence to the frame of the machine, 80 through the wire connection 125.

When the machine is operating as a generator, the flow of current will be as follows: from the armature, across the brush 79, through the wire 127, contact plates 128 85 and 129, through the shunt windings 130, and from the wire 127^a, to the fine winding 96 of the cut-out relay, via wire 131.

Now, as soon as the relay builds up sufficiently to attract the armature 97, the contact plate 53 will be engaged by the armature and the circuit closed through the wire 52, back to the battery, via wire 45, across the battery to the frame of the machine and thence back to the armature, via wire 134. 90

The mechanical connection 120, which is adapted to be operated to close the cut-out relay is provided with an insulated head portion 121, which is so arranged that it will engage with the armature of the cut-out 100 relay, under the effect of the spring 120^b which becomes effective as soon as the rod 67 is drawn rearwardly.

It will of course be apparent that the movable motor brush must be insulated 105 both from the contact plates 129 and 128, and from the operating rod 67.

When a machine or system of the type shown in Fig. 9 is employed, the successive operations of the various elements or units 110 will be as follows:

For instance, when it is desired to operate the machine as a motor, for starting purposes, the main operating member 69^b, see Fig. 2, will be depressed in such a manner 115 as to draw the rod 67 in the direction of the arrow 85 and the initial movement of this rod 67 will permit the spring 120^b to actuate the arm 120 so as to move the armature 97 of the cut-out relay to close the contacts points 98. This will permit a flow of current from the battery, through the generator windings to operate the armature at a slow speed, as has been described heretofore.

Upon a further movement of the rod 67, the shifting of the gearing 91 into engagement with the armature pinion 92 and the toothed portion 23 of the fly-wheel, will take place, a partial engagement of these 130

gear wheels being effected during the slow movement of the armature described above, inasmuch as this slow movement of the armature will pick up the gearing 91 and prevent the blocking of the gear wheels by the alinement of the teeth of the gear wheel 91^a and the pinion 92.

Upon a still further movement of the rod 67, the brush-holder 124 will be pulled downwardly by the spring 105 into engagement with the motor commutator and thus establish the motor circuit.

However, as soon as this brush-holder is drawn downwardly, the contact plates 128 and 129 will be separated by the resilient action of the plate 129, which is preferably made of spring material, the normal tendency thereof being to lie spaced apart from the contact plate 128, so as to break the generator circuit. It will be understood that when the brush-holder is in its raised position, it maintains these contact plates in contact making position, against the resiliency of the plate 129.

When the engine has become self-operating, the main operating member 69^b will be released and will return to its normal position in the usual manner, and consequently cause a return movement of the rod 67 in the direction of the arrow 85^a, shown in Fig. 9. This return movement of the rod 67 will move the gearing 91 so as to disconnect the engine from the motor and will also cause the release of the armature 97 of the cut-out relay, by moving the arm 120, and it will furthermore actuate the brush-holder 124 so as to break the motor circuit and to close the contact plates 129 and 128, to establish the generator circuit.

In Figs. 11, 12, 13 and 14, a still further modified form for securing the slow initial movement of the motor, preliminary to its actual starting operation, is set forth. In this form, the movable motor brush-holder is divided into two elements 139 and 140, insulated from each other, and capable of independent movement to a certain degree. Instead of passing the current through the generator windings in this instance, to secure a slow initial operation of the armature, the motor winding itself is employed, but is provided with a resistance element 141 which is placed directly in series with the motor circuit. This resistance element may be made of any suitable material, such as nichrome wire, and is positioned between the two insulated portions 139 and 140 of the brush-holder. If desired, this resistance unit may constitute a spring 141^a, as is shown in Fig. 12, and thus normally maintain the independent elements of the brush-holder in spaced relation, or as is clearly shown in Figs. 11 and 14, a separate and independent spring 145 may be employed,

the resistance unit 141 being entirely separate from the spring element.

The portion 139 of the brush-holder is provided with an angle arm which carries a roller 150, positioned in the slot 151 formed in one end 152 of the lever 153.

The operation of the type of machine or system shown in Figs. 11 and 12 will be as follows:

When it is desired to operate the machine as a motor for starting purposes, it is simply necessary to depress the main operating member, shown at 69^b in Fig. 2. The depression of this main operating member will draw the rod 67 rearwardly in the direction of the arrow 67^a, shown in Figs. 11 and 12, and this will first effect the coupling up of the electric machine as a motor to the engine, by enmeshing the gearing 91 with the pinion 92, and the toothed portion 23 of the fly-wheel.

It will be understood, however, that the engagement of the above mentioned gearing will not take place until after a slow initial movement has been imparted to the armature of the machine.

In this modified form, the initial operation of the machine as a motor is secured by the operation of the movable motor brush, in such a manner that the first movement will tend to break the generator circuit by the movement of the arm 139 or from the contact 80, and also the movement of the arm 140 toward the armature. This will place the brush-holder in such a position as to break not only the generator circuit, but also the motor circuit, thus leaving a time interval when both the motor and generator circuits will be broken. However, upon a continued movement, the motor brush 62 will be brought into engagement with the motor commutator, and this, of course, will establish the motor circuit.

However, as soon as the brush 62 engages with its motor commutator, the motor circuit will be completed for the slow initial movement. It will now be obvious by referring to Fig. 11 that all current flowing through this circuit must necessarily pass through the resistance element 141, inasmuch as the spring 141^a shown in Fig. 11 is of insulating material. On a continued movement of the rod 67 in the direction of the arrow 67^a, see Figs. 11 and 12, the portion 139 of the brush-holder will be depressed further, relative to both the commutator and to the portion 140 of the brush-holder, inasmuch as it is impossible for this portion 140 of the brush-holder to move farther because of its engagement with the motor commutator.

Now, as soon as the portion 139 contacts with the portion 140 of the brush-holder, the resistance unit 141 will be short-circuited

and thus a full flow of current through the motor circuit will be permitted. In Fig. 12, it will be noted that the separate resistance unit 141 is eliminated by combining the resistance unit directly with the spring. This simply requires that the spring be made of any suitable resistance material, to perform the required functions of both the spring and the resistance unit. In Fig. 13, the 10 spring 105 will assist in bringing the motor brush down into contact with the motor commutator.

While the form of mechanism herein shown and described constitutes a preferred 15 form of embodiment of the invention, it is to be understood that other forms might be adopted, all coming within the scope of the claims which follow.

What we claim is as follows:

20 1. In a starting device for engines, the combination with an engine and a starting device therefor, comprising a dynamo-electric-machine, adapted to operate as a motor for starting purposes, and as a generator for charging purposes; a source of current having motor and generator circuit connections with said electric machine, including commutator brushes; and means for operating one of said brushes to select the motor 25 circuit connections and to break the generator circuit connections during the starting operation.

25 2. In a starting device for engines, the combination with an engine and a starting device therefor, comprising a dynamo-electric-machine adapted to operate as a motor for starting purposes and as a generator for charging purposes; a source of current having independent motor and generator 30 circuit connections with said electric machine, including commutator brushes, one of said commutator brushes being normally positioned to complete the generator circuit and to break the motor circuit.

35 3. In a starting device for engines, the combination with an engine and a starting device therefor, comprising a dynamo-electric-machine adapted to operate as a motor for starting purposes and as a generator for charging purposes; a source of current having independent motor and generator 40 circuit connections with said electric machine, including commutator brushes, one of said commutator brushes being normally positioned to complete the generator circuit and to break the motor circuit; and means 45 operable relative to said brush to break the generator circuit and to make the motor circuit for starting purposes.

50 4. In a starting device for engines, the combination with an engine and a starting device therefor, comprising a dynamo-electric-machine, adapted to operate as a motor for starting purposes and as a generator for

55 charging purposes; a source of current having motor and generator circuit connections with said electric machine, including commutator brushes, one of said brushes being normally positioned to break the motor circuit and make the generator circuit; shift- 60 able coupling means for connecting the electric machine as a motor to the engine for starting purposes; and a main operating member operable relative to said coupling means to disconnect the engine and motor 65 and to break the electrical connection between the source of current and the motor and establish the generator connections.

70 5. In a starting device for engines, the combination with an engine and a starting device therefor, comprising an electric machine; operable as a motor for starting and as a generator for charging purposes, mechanical connections operable to connect said machine and engine together for starting and generating purposes; a source of current; motor and generator circuit connections between said source of current and the electric machine; commutator brushes for said machine, included in said circuit 75 connections; and means operable to normally maintain one of said brushes in position to open the motor circuit connections, and to disengage the mechanical connections used for starting purposes.

80 6. In a starting device for engines, the combination with an engine and a starting device therefor, comprising a dynamo electric machine operable as a motor for starting and as a generator for charging purposes, and including motor and generator circuits having commutator brushes; a source of current; circuit connections between said source of current and the electric machine; and means operable to maintain 85 one of the commutator brushes in position to establish the generator circuit when in 90 normal position, but operable to break this circuit and to establish the motor armature circuit during the starting operation.

95 7. In a starting device for engines, the combination with an engine and a starting device therefor, comprising a dynamo electric machine operable as a motor for starting and as a generator for charging purposes, and having motor and generator armature windings; a source of current; circuit connections between said source of current and the electric machine; a plurality 100 of commutator brushes for said machine connected to the motor and generator armature windings; and means for maintaining one of the commutator brushes in one position to select the motor armature winding 105 and in another position to select the generator armature winding.

110 8. In a starting device for engines, the combination with an engine and a starting

device therefor, comprising a dynamo-electric-machine adapted to operate as a motor for starting purposes, and as a generator for charging purposes; a source of current having motor and generator circuit connections with the electric machine, including commutator brushes, one of said brushes being normally positioned to break the motor circuit and make the generator circuit; means for mechanically connecting the electric machine as a motor to the engine for starting purposes; and a main operating member having a sequence of operations to initially close certain of said circuit connections to operate the electric machine as a motor at a slow initial speed; and secondly to effect the shifting of the coupling means to mechanically connect the electric machine to the engine; and thirdly to operate relative to the displaced brush to permit the same to break the generator circuit and to make the motor circuit.

9. In a starting device for engines, the combination with an engine and a starting device therefor, comprising a dynamo-electric-machine, adapted to operate as a motor for starting purposes, and as a generator for charging purposes; a source of current having motor and generator circuit connections with the electric machine, including commutator brushes, one of said brushes being normally positioned to break the motor circuit and make the generator circuit; means for mechanically connecting the electric machine as a motor to the engine for starting purposes; and a main operating member having a sequence of operations to initially close certain of said circuit connections to operate the electric machine as a motor, at a slow initial speed, and secondly, to effect the shifting of the coupling means to mechanically connect the electric machine to the engine.

10. In an electric system, the combination with independent sets of field and armature windings; independent sets of commutator brushes for said windings; and means for maintaining one of said sets of commutator brushes out of electrical connection with its set of windings and establishing electrical connection through the other set of windings, and operable to make said first set of connections and to break the last named circuit connection.

11. In an electrical system, the combination with a dynamo-electric-machine, having independent sets of field and armature windings; independent commutators for each set of armature windings; a set of brushes for each of said commutators; and means for moving one of the commutator brushes to select the windings to be brought into operation.

12. In an electrical system, the combina-

tion with a dynamo-electric-machine, having a plurality of independent sets of field and armature windings; of an independent commutator connected with each of said windings; a set of commutator brushes for each of said commutators; and means normally maintaining one of said brushes in position to break the electrical connections with one of said sets of windings and to establish electrical connection with the other set of windings.

13. In an electrical system, the combination with a dynamo-electric-machine, having a plurality of independent sets of field and armature windings; of an independent commutator connected with each of said windings; a set of commutator brushes for each of said commutators; and means normally maintaining one of said brushes in position to break the electrical connections with one of said sets of windings and to establish electrical connection with another set of windings, and operable to establish the first named electrical connections and to break the electrical connections with the other set of windings.

14. In an engine starting system, the combination with an engine and a starting device therefor, comprising a dynamo-electric-machine, having motor and generator windings; a common armature; independent motor and generator windings mounted thereon; a source of current; motor and generator circuits connected to the source of current and the respective windings of the machine; independent sets of commutator brushes connected with the said windings; and means for normally maintaining one of the brushes in position to break the motor circuit, and to establish the generator circuit.

15. In an engine starting system, the combination with an engine and a starting device therefor, comprising a dynamo-electric-machine, having a common armature, with independent motor and generator windings mounted thereon; a source of current; motor and generator circuits connected to the respective windings of the machine; independent sets of commutator brushes connected with the said windings; means for normally maintaining one of the brushes connected with the motor circuit in position to break the motor circuit, but to establish the generator circuit; and means operable relative to the displaced brush to close the motor circuit and to break the generator circuit throughout the use of the machine as a motor.

16. In an electrical system, the combination with a source of current, and a dynamo-electric-machine; motor and generator circuit connections between said source of current and machine; a common armature

mounted on said machine and having independent motor and generator windings mounted thereon; independent sets of brushes connected to the motor and generator windings, and adapted to contact with said armature; and means for normally maintaining one of the motor brushes in position to break the motor circuit and to make the generator circuit and operable to release the motor brush to break the generator circuit and make the motor circuit.

17. In an engine starting device, the combination with an engine and a starting device therefor, comprising a dynamo-electric machine, a storage battery having electrical connection therewith; means included in said electrical connection, comprising an automatic current interrupter, adapted to break the circuit connection between said electric machine and battery, when the voltage of the electric machine is less than the voltage of the battery; and mechanical means for operating said automatic current interrupter, to permit current to flow from the battery to the generator windings of the electric machine, to operate the machine as a motor, as a preliminary to the actual starting operation.

18. In an engine starting device, the combination with an engine and a starting device therefor, comprising a dynamo-electric machine; a storage battery having electrical connection therewith; means included in said electrical connection, comprising an automatic current interrupter having an armature adapted to break the circuit connection between said electric machine and battery, when the voltage of the electric machine is less than the voltage of the battery; and mechanical means for operating said armature to close the circuit connections, whereby current will flow from the battery to the electric machine, to actuate the same as a motor.

19. In an engine starting device, the combination with an engine and a starting device therefor, comprising a motor and a generator; means for mechanically connecting the engine and the motor; an accumulator

adapted to be electrically connected with the motor and the generator; and means for normally dis-establishing the electrical connection between the accumulator and the motor, and establishing connection between the accumulator and the generator; and a current interrupter for maintaining the generator circuit open, at such times as the voltage across the generator is less than the voltage across the battery terminals; a main operating member for controlling the mechanical connections between the motor and the engine, and having provisions for mechanically operating the automatic current interrupter to permit a flow of current from the battery to the generator, to operate the machine as a motor through the generator windings.

20. In an engine starting device, the combination with an engine and a starting device therefor comprising a dynamo electric machine operable as a motor for starting purposes and as a generator for charging purposes; shiftable means for mechanically connecting the engine and electric machine; of a source of current; motor and generator circuit connections between said source of current and the electric machine; means for opening the generator circuit connections when the engine is at rest; a plurality of commutator brushes for the electric machine and means for maintaining one of said brushes in position to normally break the motor circuit and to form a part of the generator circuit; and means for closing the generator circuit and to shift the mechanical connections previous to the starting operation, whereby the electric machine will operate at slow speed as a motor during the shifting of the mechanical connections.

In testimony whereof we affix our signatures, in the presence of two subscribing witnesses.

CHARLES F. KETTERING.
